UNITED STATES PATENT OFFICE.

HENRY W. MULLENAX, OF MONTEREY, VIRGINIA.

CONVERTIBLE HILLSIDE REVERSIBLE PLOW.

1,262,232.

Specification of Letters Patent.

Patented Apr. 9, 1918.

Application filed July 10, 1917. Serial No. 179,702.

To all whom it may concern:

Be it known that I, HENRY W. MULLENAX, a citizen of the United States, residing at Monterey, in the county of Highland and State of Virginia, have invented a new and useful Convertible Hillside Reversible Plow, of which the following is a specification.

The invention relates to a convertible hillside reversible plow.

10 The primary object of the invention is the provision of a plow of this character, wherein on adjusting the double mold-board of the same, an auxiliary mold-board can be positioned so that the plow will be converted 15 from a hillside to a level land or other plow, thereby permitting the working of any character of ground and particularly level ground or a hillside, the plow being readily adjusted to convert the same for the particular use required, and the reversing of its 20 mold-board can be easily effected with despatch, without raising or upsetting the plow.

Another object of the invention is the provision of a plow of this character, wherein 25 the construction thereof is novel in form to assure the convenient adjustment of the same and the perfect working thereof for the positive turning of earth on level or grade surfaces, the plow being readily movable from one point to another without throwing it upon its side as usual, when desired to transfer said plow from one field to another.

30 A further object of the invention is the provision of a plow of this character, which is comparatively simple in construction, thoroughly reliable and efficient in its operation, readily and easily adjusted, strong, durable, and inexpensive in manufacture.

40 Other objects will be in part obvious and in part hereinafter pointed out.

The invention accordingly consists in the features of construction, the combination of elements and arrangement of parts, which 45 will be exemplified in the construction hereinafter set forth, and the scope of the application of which will be indicated in the following claims.

In the accompanying drawings:—

50 Figure 1 is a side elevation of a plow constructed in accordance with the invention, the plow being partly broken away.

Fig. 2 is a top plan view.

55 Fig. 3 is a fragmentary enlarged side elevation, looking toward the opposite side from that shown in Fig. 1.

Fig. 4 is a fragmentary rear elevation.

Fig. 5 is a sectional view, taken approximately on the line 5—5 of Fig. 1.

Fig. 6 is a fragmentary detail elevation 60 showing in section the swiveled connection of the auxiliary mold-board standard and sleeve.

Fig. 7 is a fragmentary detail view of the yoke arm for said connection shown in 65 Fig. 6.

Fig. 8 is a plan view of the foot pedal and catch arms for the reversible mold-board.

Fig. 9 is a plan view of the double right and left hand mold-board and point. 70

Similar reference characters designate like parts throughout the several figures.

Referring to the drawings in detail, A designates the main or draft beam, B the standard, C the forwardly directed runner, D the 75 double right and left hand mold-board, and E the handles of the plow, the essential details of which will be hereinafter fully described.

On the main or draft beam A of the plow 80 at the front end thereof is the usual clevis hanger 10, while spaced rearwardly of the front end of said beam and secured to its under side is a bearing 11 for the mounting of the adjusting device for a traction wheel 85 12. The wheel 12, when adjusted permits the dipping of the plow for varying the depth of cutting action thereof, and also allows the plow to be transported from one point to another, without necessitating the 90 turning of the plow upon either side thereof, during the transfer or moving thereof from one field to another, as is usual. The adjusting device for the wheel comprises a leg 13, in which is journaled the wheel 12, and this leg is swingingly supported upon a pivot 14 mounted in the bearing 11 for the vertical adjustment of said wheel, and is formed with an arm extension 15, straddling the beam A to which is loosely connected the 100 forward end of an actuating rod 16, having its rear end pivotally connected to a throw lever 17 pivoted at 18 on one side of the beam A for swinging movement, the lever being provided with a hand release latch 105 pawl 18 for locking engagement with a segment 19 fixed to the beam A and handle bars E, respectively, the segment 19 being formed with a plurality of notches 20 at proper intervals therein, for receiving the pawl 18 to 110 hold the throw lever 17 locked in its adjusted position. The lever 17, when moved, will

cause the adjustment of the wheel 12 for the raising and lowering thereof in the use of the plow.

The runner C, extending forwardly from the standard B of the plow, has on its bottom face a shoe 21 to prevent wear of the runner. The forward end of the runner C is provided with a front trunnion 22, while spaced rearwardly a distance therefrom either mounted in or integral with the runner C is a rear trunnion 23, these trunnions being designed to pivotally support a double right and left hand plow point and mold board 24 and 25 respectively, which are united to each other in any desirable manner. The point 24, is formed with a suitable socket for receiving the trunnion 22, while at the inner faces of the wings of the double mold-board are eyes 25^a, in which engage the hook ends 26 of a Y-shaped brace 27, which is pivotally engaged with the rear trunnion 23 and carries a swinging latch hook 28, pivoted thereto which engages with a keeper 29 mounted on the inner side of the mold-board 25, as is clearly shown in Fig. 3 of the drawings, and in this manner, the mold-board is detachably fastened for the pivotal mounting thereon upon the runner. The pivotal mounting of the mold-board permits the same to be swung from the right hand side to the left hand side of the plow, for the reversing thereof when used as a hillside plow. The outer faces of the side wings of the mold-board 25 forwardly thereof are formed with curvilinear depressions 30 which constitute seats for an auxiliary mold-board employed for converting the hillside plow into a level land plow, in a manner to be hereinafter fully described.

The auxiliary mold-board comprises a plate 31, preferably of the shape illustrated in Fig. 1 of the drawings, having a stem 45 or standard 32, which is passed through a suitable opening 33 formed in the beam A for sliding and rotary movement on the adjustment of the auxiliary mold-board, the stem or standard 32 rises above the beam A and has loosely fitted thereon a sleeve 34, which is formed with a rearwardly inclined segment 35, and passed transversely through this sleeve 34 is a coupling pin 36, which engages in a circumferential annular groove 37 formed in the stem or standard 32, so that the latter will be swiveled for rotation within the sleeve. Pivotedly connected to the coupling pin 36 is the yoke end 38 of the adjusting arm 39 of a throw lever 40, which is swingingly supported on the pivot 18, the latter serving the dual function of a pivot for both of the levers 17 and 40, hereinbefore described. The lever 40 carries a hand released latch pawl 41, which engages with a segment 42 pro-

vided with notches 43 at the proper intervals apart to receive the pawl 41, and in this manner, the auxiliary mold-board can be locked in adjusted position, either raised out of the path of reversing movement of the mold-board 25 or in lowered position for engagement with the seats 30 therein, which extend in forwardly divergent relation from the crest of said mold-board 25 through the outer edges thereof, and when the auxiliary mold board 31 is thus engaged, it forms a continuation of the mold board 25, to insure the turning of the earth when the plow is working in level land. The seating of the auxiliary mold-board 31 in the reversible mold-board 25, when either at the right hand side or left hand side of the plow, effects a smooth surface throughout the mold-boards 25 and 31, and this auxiliary mold-board, when in said position, will have its edge at the juncture thereof with the double mold-board 25 in contact, so that the outer surfaces of said parts will be flush with each other. Suitably fixed to the standard or stem 32 of the auxiliary mold-board 31 above the segment 35 is a handle or lever 44 for turning the auxiliary mold-board to properly adjust the same relative to the mold board 25, when reversed from one side to the other of the plow.

The handle or lever 44 is formed with a latch nib 45, which is adapted for engagement in any one of the notches 46 in the upper face of the segment 35, so that the auxiliary mold-board when in raised position can be located centrally of the line of draft of the plow, and when in lowered position held fast in its set relation to the reversible mold-board. 105

Pivoted on the standard B at the rear end thereof is a pedal 47 to which are loosely connected catch arms 48 having forked catch extremities 49 for engagement with the arms of the Y-shaped brace 27 to lock the double mold-board 25 in its reversed positions, the pedal 47 being accessible for engaging the foot of the operator of the plow therewith to lock and unlock the double mold board. The arms 48 are slidably through suitable guides 50 on the standard B of the plow when the arms are moved for the latching or unlatching of the double mold-board. 115

Suitably supported on the standard B is a resilient latch 51, which engages with a toothed segment 52 on the pedal 47 to lock the pedal in adjusted position. 120

In the working of the plow, it is obvious that the double mold-board 25 can be reversed to either side, thereby converting the plow into a right hand or a left hand hillside plow. Now, when it is desired to convert the plow to work in level land, the mold-board 24 is adjusted to either side 130

and to permit this, the auxiliary mold-board 31 is raised above the path of movement thereof, by actuating the throw lever 40, and thereafter said auxiliary mold-board 5 31 is brought into contacting relation to the adjusted double mold-board 25 for the engagement of the auxiliary mold-board 31 in either seat 30, and this is accomplished by the lowering of the auxiliary mold-board 10 from its raised position and rotating the standard or stem 32 thereof to bring the said board into its proper adjusted position.

The reversible double mold-board 25 and the auxiliary mold-board 31, when properly 15 adjusted, are locked in rigid relative positions with respect to each other for the employment of the plow in the working of level ground. Therefore, it will be clearly obvious that the plow is readily convertible 20 from a hillside to a level land plow, or vice versa, and such plow will turn any character of earth in the operation thereof.

From the foregoing, it is thought that the construction and manner of operation of the 25 invention will be clearly understood, and, therefore, a more extended explanation has been omitted.

What is claimed is:—

1. In a plow of the character described, 30 a standard having a forwardly extending runner, a double right and left hand mold-board pivotally supported by the runner and having curvilinear depressions to form seats on opposite sides of the crest of the 35 same, means for locking the double mold-board in its adjusted position to either side of the standard, an auxiliary mold-board for engagement in either of the seats and having a contour to lie flush with the outer 40 surface of the double mold-board when at the right or left hand side, and means for adjustment of the auxiliary mold-board and also for locking it when adjusted.

2. In a plow of the character described, 45 comprising a main beam and having a standard, a runner extending forwardly from the lower end of the standard, a reversible double mold-board on the runner for adjustment to either side thereof, a foot 50 pedal pivoted to the standard rearwardly thereof, a substantially Y-shaped brace for the double mold board, and catch arms pivoted to the pedal and slidably connected with the standard and having forked catch 55 ends for engagement with the limbs of the Y-shaped brace to latch the double mold-board in adjusted position to either side of the runner.

3. In a plow of the character described, 60 comprising a main beam having a standard, a runner extending forwardly from the lower end of the standard, a reversible double mold-board on the runner for adjustment to either side thereof, a foot pedal 65 pivoted to the standard rearwardly thereof,

a substantially Y-shaped brace for the double mold-board, catch arms pivoted to the pedal and slidably connected with the standard and having forked catch ends for engagement with the limbs of the Y-shaped 70 brace to latch the double mold-board in adjusted position to either side of the runner, and a resilient latch supported by the standard for locking the pedal at a neutral point or reversely shifted positions for latching 75 the double mold-board.

4. In a plow of the character described, a standard, a double right and left hand mold-board swingingly supported forwardly of the standard and having seats in the outer 80 face thereof, a stem slidably and rotatably engaged forwardly of the standard, an auxiliary mold-board on the stem and engageable in either of the seats in the double mold-board, whereby the exposed surface of 85 the auxiliary mold-board will be flush with the outer surface of the double mold board when in shifted position to either side of the standard, means for raising and lowering the stem for moving the auxiliary mold-board into and out of registration with the 90 seats, and means for locking the stem to hold the auxiliary mold board engaged in either of the seats.

5. In a plow of the character described, 95 a standard, a double right and left hand mold-board swingingly supported forwardly of the standard and having seats in the outer face thereof, a stem slidably and rotatably engaged forwardly of the standard, an auxiliary mold-board on the stem and engageable in either of the seats in the double mold-board, whereby the exposed surface of the auxiliary mold-board will be flush 100 with the outer surface of the double mold board when in shifted position to either side of the standard, a throw lever swingingly supported and having a yoke arm, a sleeve swiveled to the stem and pivoted in the yoke arm, a segment on the sleeve, and a handle 110 on the stem for rotating the same and having a nib for locking engagement with the segment.

6. In a plow of the character described, a standard, a double right and left hand mold-board swingingly supported forwardly of the standard and having seats in the outer face thereof, a stem slidably and rotatably engaged forwardly of the standard, an auxiliary mold-board on the stem and engageable in either of the seats in the double mold-board, whereby the exposed surface of the auxiliary mold-board will be flush with the outer surface of the double mold-board, when in shifted position to either side of 120 the standard, a throw lever swingingly supported and having a yoke arm, a sleeve swiveled to the stem and pivoted in the yoke arm, a segment on the sleeve, a handle on the stem for rotating the same and having 125 130

- a nib for locking engagement with the segment, and means for locking the throw arm in adjusted position for raising the auxiliary mold-board out of the path of movement of the double mold-board and into the seats in the latter.
7. The combination with a plow having a reversible double mold-board provided with seats at opposite sides of the longitudinal 10 medial portion thereof and forwardly in the same, of an auxiliary mold-board for engagement in either of the seats and constituting a continuation of said double mold-board for the turning of soil when adjusted 15 to either side of the line of draft of the plow, and means for adjusting the auxiliary mold-board into and from the seats.
8. The combination with a plow having a reversible double mold-board provided 20 with seats at opposite sides of the longitudinal medial portion thereof and forwardly in the same, of an auxiliary mold-board for engagement in either of the seats and constituting a continuation of said double mold-board for the turning of soil when adjusted 25 to either side of the line of draft of the plow, and means for adjusting the auxiliary

mold-board into and from the seats, and means for locking the auxiliary mold-board in adjusted positions.

9. In a plow of the character described, the combination with a swivel reversible mold-board, of an auxiliary mold-board movable into position for engagement with said reversible mold-board to form a continuation thereof when at the right or left hand side of the plow.

10. In a plow of the character described, the combination with a swivel reversible mold-board, of an auxiliary mold-board movable into position for engagement with said reversible mold-board to form a continuation thereof when at the right or left hand side of the plow, and independent means for locking the reversible mold-board and the auxiliary mold-board in adjusted position.

In testimony, that I claim the foregoing as my own, I have hereto affixed my signature in the presence of two witnesses.

H. W. MULLENAX.
